(57) **CLAIM**

The ornamental design for a side cover for motorcycle, as shown and described.

DESCRIPTION

FIG. 1 is a perspective view from the left side of a side cover for motorcycle;

FIG. 2 is a perspective view from the right side thereof;

FIG. 3 is a perspective view from the left side thereof;

FIG. 4 is a perspective view from the right side thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a right side elevation view thereof;

FIG. 10 is a left side elevation view thereof; and,

FIG. 11 is a referential view showing use thereof.

The broken lines illustrate environmental structure only and form no part of the claimed design.
